UNITED STATES PATENT OFFICE.

JOHN J. HEEDY, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS VESSEL.

40,672.

Specification for Design.

Patented May 3, 1910.

Application filed February 25, 1910. Serial No. 616,035. Term of patent 14 years.

To all whom it may concern:

Be it known that I, JOHN J. HEEDY, a citizen of the United States, and residing at Moundsville, in the county of Marshall and State of West Virginia, have invented a certain new, original, and ornamental Design for a Glass Vessel, shown in the accompanying drawing, which is a view in perspective of the same.

I claim:

The ornamental design for a glass vessel, as shown.

J. J. HEEDY.
